GRATING

Herbert H. Bunker, Jersey City, N. J., assignor to
 Kerlow Steel Flooring Company, Jersey City,
 N. J., a corporation of New Jersey

Application October 15, 1942, Serial No. 462,102

3 Claims. (Cl. 94—30)

This invention relates to non-metallic gratings suitable for use as ventilated flooring. Among the objects of the invention is to provide a non-metallic grating structure having wearing and anti-slip characteristics which render it practical for industrial uses as well as for ventilated flooring in general.

Further and other objects of the present invention will be hereinafter set forth in the accompanying specification and claims and demonstrated by the drawing which shows by way of illustration a preferred embodiment and the principle of my invention and what I now consider the best mode in which I have contemplated applying that principle. Other embodiments of the invention employing the same principle may be used and structural changes made as desired by those skilled in the art within the spirit of the appended claims and without departing from the present invention.

In the drawing,

Fig. 1 is a plan of a corner of a grating panel.
 Fig. 2 is a section on line 2—2 of Fig. 1.

Fig. 3 is a section on line 3—3 of Fig. 1.

The portion of the grating illustrated in Fig. 1 covers sufficient area to illustrate a manner of constructing a panel or floor area according to the present invention, but it will be understood that the grating may be made up in any size of panel desired and in accordance with practices prevailing in the use of metallic grating.

The panel comprises beam elements or girders 10, arranged in parallel rows and spaced from each other. These are joined by cross-members 11 which are arranged parallel to each other and in spaced relationship. The beam-elements are deeper than the cross-members but the upper edges of both are disposed in the upper surface or floor of the grating.

Each beam 10 is provided with notches 12, Fig. 2, in its upper edge for engaging the sides of the cross-members at the places where the floor members intersect. The cross-members also have complementary notches 13, Fig. 3, in their under edges which engage the sides of the beams. The bottoms 14 of notches 12 and 13 are so situated with respect to the floor of the grating as to position the upper edges of the beams and cross-members in a common plane. The notches are preferably proportioned to cause snug engagement between their vertical walls and adjacent surfaces of the floor members.

As may be seen clearly in Fig. 3, the beams have a stepped cross-section with the narrowest width of the cross-sections at their upper edges. The depth of the cross-members is such as to locate

their lower edges below the shoulders 15, 16, whereby the side walls of notches 13 extend over and contact with the side walls of the beams 10 at their greatest width. This construction stiffens the beam elements against lateral deflection.

The grating thus far described is especially suitable for making of wood. Adhesives may be used for making firm the connections between the crossing members, or nails or other wood joining elements may be used. The wood can be sealed in with resinous lacquers for making the grating impervious to oils, acid and caustic drippings to which industrial gratings are frequently subjected.

15 The upper surface of the grating is provided with metallic strips 18, which, in the embodiment of the invention illustrated in the drawing, extend lengthwise along the upper edges of the beams. While the designs of these strips may assume proportions different from those illustrated, it is intended that they project laterally of their center lines so that each strip will provide a laterally expanded tread surface by which their anti-friction capacity is increased. The wave construction illustrated is suitable for this purpose. The wave or crimp formation can be easily imparted to flat strips of iron in a well-known manner.

20 The strips are deep enough to be embedded in the beams and extend above their upper edges whereby they protect the floor of the grating and improve the frictional resistance of the floor against slipping by a user.

25 While the strips could be embedded in the cross-members, I prefer to set them on the beams and continue them without interruption over the cross-members and thereby provide a means for anchoring the cross-members in place. The whole panel is thereby rendered more rigid and rugged against surface wear.

30 For fastening the strips in place, they may be forced edgewise into the wooden members by the use of a press. In such procedure they can be made to cut their own receiving grooves and firmly 35 secure themselves.

35 What is claimed is:

1. In a ventilated floor grating, the combination comprising parallel non-metallic beam elements running lengthwise of the grating and spaced from each other, parallel non-metallic cross-members running crosswise of the grating and spaced from each other, said cross-members having notches in their lower edges and said beam elements having notches in their upper edges which engage at intersections of the cross-

members and beam elements, said notches being of such depth as to contact at their bottoms and locate the upper edges of the beam elements and cross-bars in the floor of the grating, and metallic strips extending along the whole length of the upper edges of the beam elements and continuing over a series of cross-members for providing wear-protection for the non-metallic floor surface, said metallic strips being embedded below the floor surface of the grating and interlocking the beam elements and cross-members at their intersections and thereby locking the cross-members down with the bottoms of the notches in contacting relationship.

2. In a ventilated floor grating, the combination comprising parallel non-metallic beam elements running lengthwise of the grating and spaced from each other, each of said beam elements having a depth greater than its width and a reduced cross-sectional area above their lower edges and extending to the floor surface of the grating, parallel non-metallic cross-members running crosswise of the grating and spaced from each other, said cross-members having notches in their lower edges and said girder elements having notches in their upper edges which engage with the sides of the beam elements and cross-members respectively, said notches being of such

depth as to provide contact of the bottoms of joined notches and locate the upper edges of the beam elements and cross-members in a plane, and metallic strips embedded in and longitudinally along the whole length of the upper edges of the beam elements and in and across the cross-members where the cross-members intersect the beam elements so as to provide wear-resistant material in the floor of the grating surface and lock the non-metallic beams and cross-members together.

5 3. A ventilated floor comprising parallel beams spaced from each other, parallel cross-members spaced from each other and crossing said beams, said beams and cross-members being non-metallic and provided with notches at their intersections for locking intersecting beams and cross-members together in a composite ventilated panel with the upper edges of the beams and cross-members lying in a single plane, metallic strips embedded in the upper edges of said beams with their upper edges extending above the upper edges of the beams for providing anti-slip characteristics to the floor surface of the panel, said metallic strips running the whole length of the beams and being crimped cross-wise of the beams to provide reverse beads in the strips for effecting reduction in the possibility of slipping over the surface of the panel.
